UNITED STATES PATENT OFFICE.

COLIN MACRAE INGERSOLL, OF NEW YORK, N. Y.

MACHINE FOR SURFACING ROADS, PAVEMENTS, &c.

No. 905,190.

Specification of Letters Patent.

Patented Dec. 1, 1908.

Application filed April 21, 1908. Serial No. 428,366.

To all whom it may concern:

Be it known that I, COLIN MACRAE INGERSOLL, a citizen of the United States, residing at New York city, in the county of New York and State of New York, have invented certain new and useful Improvements in Machines for Surfacing Roads, Pavements, &c., of which the following is a specification, reference being had therein to the accompanying drawings.

This invention relates to a machine for applying a liquid bonding and surfacing material to macadam or other beds of roads, pavements and the like, whereby the ingredients of the upper stratum or strata of the beds are bonded together and given a finishing surface through which dirt and water do not work. The material used is preferably coal-tar or a tarry composition. Road and pavement beds thus treated dry quickly after rainfalls, and are readily cleaned and repaired.

Among the objects of the present invention are: the provision of a surfacing machine that is economical to construct, operate and maintain, and that is adapted to heat and apply hot, tarry-like bonding and surfacing material, under pressure, so that it penetrates downwardly between the macadam or other roadbed constituents, and thoroughly bonds and covers them; and also to make the machine in such wise that it is not dependent on local water supplies for maintenance of its principal operations during its tours of use.

My new machine comprises the following principal factors, which are here stated for better understanding of the following description:—a wheeled vehicle; a driving mechanism therefor; an internal combustion engine; an air compressor; a reservoir to hold the bonding and surfacing material; a discharging device for such material; a road-cleaning brush in advance of the discharging device; and drag-brushes rearward of the discharging device; the exhaust gases of the engine being used at will to heat the contents of the reservoir; the air compressor being used, at will, not only to supply compressed air above the contents of the reservoir and thus secure the uniform discharge of the material under pressure, but also, when desired, to charge the reservoir automatically. Suitable clutches or the like are provided to connect and disconnect the air compressor, engine and driving gear, so

that the same may be run either simultaneously or independently as may be required. A compressed air tank is also preferably provided, between the air compressor and the reservoir, to supply compressed air to the upper part of the reservoir, above its contents, when the compressor is not in operation.

In the accompanying drawings, illustrating the principle of the invention and the best mode now known to me of applying that principle, Figure 1 is an elevation of the machine, partly in side view and partly in vertical section, at a line corresponding to line 1—1 of Fig. 3. This view also shows a container of the road bonding and surfacing material, exterior to the machine, and from which the material may be automatically conveyed to the reservoir to charge it. Fig. 2 is an enlarged view, partly in side elevation and partly in vertical section, at line 1—1 of Fig. 3, more plainly illustrating the mechanical connection of the engine with the air compressor and supply reservoir, and also the mode of mounting and operating the road-cleaning brush. Fig. 3 is a top-plan view of the entire machine. Fig. 4 is an enlarged top-plan view of a portion of the machine, parts being broken away for greater clearness. Fig. 5 is a rear-end view of the machine. Fig. 6 is a vertical, sectional view, at line 6—6 of Fig. 7, of one of the discharging heads of the reservoir. Fig. 7 is a side elevation of one of the discharging heads. Fig. 8 is a vertical, central view of the air compressor, showing its inlet and outlet valves and piston; and also an evaporating device for cooling the cylinder of the compressor. Fig. 9 is an enlarged elevation showing a detail of mechanism for mounting and rotating the road-cleaning brush. Fig. 10 is a side elevation of the road-cleaning brush, and a part of its supporting and actuating mechanism. Fig. 11 is an enlarged view more clearly showing the connections of the engine with the road-cleaning brush and with the air compressor, and, on the engine shaft, the actuating gear of the vehicle driving mechanism. Fig. 12 is a vertical, sectional view illustrating one way of hinging a distributer-head to the distributing pipe. Fig. 13 is a transverse, sectional view of the construction shown in Fig. 12.

Referring to the drawings, A is the wheeled vehicle frame; B an internal combustion engine mounted on the frame; D

the rear axle of the machine, the rear wheels of which are driven from the engine; F an air compressor; R the reservoir which contains the bonding and surfacing material; 5 and C a compressed air tank which is in communication both with the air compressor and the reservoir.

Engine shaft 1 projects rearwardly of the engine, and on it is mounted a loose, slide-10 able bevel-gear 2 having an integral collar 3 toothed for engagement with and disengagement from a correspondingly toothed collar 4 mounted on shaft 1 and compelled to rotate therewith by a spline 5 (see Fig. 11). When toothed collars 3 and 4 are in engagement, bevel-gear 2 rotates with shaft 1. Collar 4 is circumferentially grooved 15 for reception of a pin (Fig. 2) on lever 6 pivoted at 7 to the frame A. Lever 6 is connected to a controlling-rod 8 extending 20 to the driver's seat, and there attached to a controlling-lever 9 provided with a pawl and ratchet mechanism 10 for holding it in position to keep the toothed collars 3 and 4 25 connected or disconnected.

The purpose of bevel-gear 2 is to drive the road-cleaning brush 24. Bevel-gear 2 meshes with a bevel-gear 11 on a vertical shaft 12, and its hub 13 rests on the upper 30 side of frame A.

Shaft 12 passes from A and through a bearing-plate 14 between the under side of frame A and the upper side of brush-carrier 15, being provided, on the under side of the brush-carrier, with a fixed collar 16 whereby, 35 in connection with hub 13, shaft 12 is kept from endwise movement. The lower end of shaft 12 is provided with a bevel-gear 17 which meshes with a bevel-gear 18 on the 40 transverse horizontal shaft 19 of the brush frame. This shaft is mounted in bearings in the opposite, downwardly extending end-hangers 20, 20 of the brush-carrier. Intermediate bearings 21, 21 for shaft 19 are 45 preferably provided. Hangers 20 are provided each with a hook 21* to engage the journals 22 of the road-cleaning brush 24 when it is desired to keep the brush above the ground. The journals of the brush are mounted in 50 the vertical slots 23 of hangers 20, in order to permit the road-cleaning brush to rise in case it encounters substantial obstacles. One of the end journals of the brush is provided with a sprocket-wheel 26, from which a 55 sprocket chain 27 passes to a sprocket-wheel 28 on a corresponding end of shaft 19. Rotation of shaft 12 compels the brush 24 to rotate and sweep the road-bed.

The road-cleaning brush, when in operation, should stand transversely of frame A, and diagonally in relation to the length thereof, so that the sweepings may be discharged to either side of the road at will. To lock and brace the brush-supporting 60 frame 15 in one or the other of such diagonal

positions, each side of frame A is provided with a pair of ears 29, against the under surfaces of which the upper surface of the brush frame rests and is thereby braced and locked when the brush frame is in a diagonal 70 position and pins 30 are through the coincident holes through the ears and brush frame.

The driving mechanism of the machine for connecting the engine with the driven rear axle D (Figs. 3 and 4) comprises a 75 short, transverse, horizontal shaft 31 and an auxiliary shaft 31^a in alinement with shaft 31, mounted in bearings 32 on frame A. The inner end of shaft 31 is provided with a fixed bevel-gear 33 which meshes with a 80 bevel-gear 34 fast on engine shaft 1. The outer end of shaft 31^a is provided with a fixed sprocket-wheel 35, from which a sprocket-chain 36 passes to a sprocket-wheel 37 on axle D. Shafts 31 and 31^a are coupled 85 together for propulsion of the machine, shaft 31^a being provided with a fixed coupling member 38 and shaft 31 being provided with a slideable coupling member 39 circumferentially grooved for the reception 90 of an end 40 of bell-crank lever 41 pivoted at 42 to frame A. A controlling-rod 43 extends from the bell-crank lever forwardly to the driver's seat, where it is provided with a controlling-lever 44 and a suitable pawl and 95 ratchet mechanism. By this construction the driving gear may be disconnected from the engine whenever desired, so that the machine as a whole may remain stationary, the engine shaft then being free to rotate, 100 when desired, without propelling the machine, in order to operate air compressor F while the vehicle is stationary.

Shaft 45 of the air compressor (Fig. 11) is extended on one side in alinement with engine shaft 1, and provided with a slideable clutch collar 46, which is compelled to rotate with shaft 45 by a spline 46* and which is adapted to engage with the supplementary clutch member 47 fast on shaft 1, whereby 110 the engine shaft and air compressor shaft are coupled together. Clutch collar 46 has a circumferential groove for reception of pins 48 in yoke lever 49 pivoted to frame A at 50. Clutch collar 46 may thus be disconnected from clutch member 47 when it is not desired to operate the air compressor.

The cylinder of the air compressor (Fig. 8) is provided with a head 51, in which an outwardly opening valve 52 and an inwardly opening valve 53 are mounted in a well known manner, head 51 being formed with passages controlled by said valves. From chamber 54 of this cylinder, (Fig. 1), a pipe 55 leads to the compressed air tank C, being provided, between the compressor and air tank, with a shut-off valve 56. The valve 53 controls a pipe 57 that is open to the air and provided with a shut-off valve 58. When valves 56 and 58 are open and the 130

piston 59 of the compressor is given a down-stroke, the air in chamber 54 is rarefied, and atmospheric pressure through pipe 57 unseats valve 53, permitting inflow of outside air into said chamber. On the up-stroke of piston 59, valve 53 is seated and valve 52 unseated, and air is pushed through pipe 55 into the compressed air chamber, which is provided with a suitable pressure-indicator 60 (the details of which are not illustrated, it not being deemed necessary to show the construction, as the same will be readily understood by all skilled in the art) to show the pressure in the air tank.

In the operation of the air compressor, heat will be generated, and the cylinder and piston consequently heated. I therefore prefer to provide the air compressor with some simple form of evaporating device whereby the cylinder may be cooled; but, for the reason that machines containing my invention may be frequently operated at considerable distances from adequate water supplies, (which would be requisite for a steam-operated machine,) I do not wish to water-jacket the cylinder of the air compressor; so I provide the same with a circumferential trough 61, at its lower end, and above the trough attach to the outer side of the cylinder a cloth wrapping 62. On any suitable support, a small can, 63, of water may be secured, and provided with a drip-pipe 64 for slow saturation of cloth 62. As the air compressor is only in occasional operation, this simple evaporating device serves to sufficiently cool the cylinder. Trough 61 catches any drippings there may be, and by holding the drip water in contact with the cylinder facilitates the cooling thereof. Any other evaporating or cooling device may be used if and when any cooling of the air compressor is necessary.

Compressed air tank C preferably surrounds reservoir R, in order to reduce the radiation of heat therefrom, and is connected by a pipe 66 with the upper part of the reservoir. The pipe is provided with a shut-off cock 67. While compressed air tank C forms, in effect, a part of the conduit connection between air compressor F and reservoir R, yet the air tank is desirably interposed, because but little pressure of compressed air in the upper part of reservoir R, above its contents, is requisite to secure a uniform discharge of the contents under pressure; and also because the air pressure would not be so uniform if the air compressor were run continuously and piped directly to the reservoir. Therefore, when compressed air tank C is charged, valve 56 may be closed and valve 67 opened, and the pressure of the compressed air in tank C be communicated to the upper surface of the contents of the reservoir R during the fall thereof in the reservoir. If the outflow of

the material is not sufficiently forcible, valve 56 may be opened and the air compressor operated. 68 is the fly-wheel of the compressor, and 69 the fly-wheel of the engine.

Reservoir R is provided, at its upper portion, with a short pipe 70, which is provided with a shut-off cock 71. The purpose of this pipe 70 is two-fold. It allows gases and fumes generated in the reservoir to escape and be observed, and it is also used as the feed-intake of the reservoir when the latter is charged. When the reservoir has been properly charged,—that is, to a line somewhat below its upper end,—and the material is heated, gases and fumes which can be observed will escape through pipe 70, valve 71 being then open. The appearance of gases and fumes of coal-tar or the like at the open end of pipe 70 shows when the same is sufficiently hot for most effective application, and then valve 71 is closed and valve 67 opened to let in compressed air, whereby the heated contents of the reservoir are forcibly expelled through the downwardly extending discharge exit 77, at the rear end of the machine and rearward of the road-cleaning brush. The lower end portion of exit 77 is provided with a shut-off valve 78, which is actuated by a controlling-rod 79 that passes forwardly to a point near the driver's seat and is there connected with a hand lever 80 whereby valve 78 is conveniently opened or closed.

To heat the contents of the reservoir, the escape gas-exhaust 81 of the engine is provided with a two-way discharge-pipe (or muffler), one branch 82 of which discharges into the open air adjacent to the engine and is provided with a shut-off valve 83. The other branch 84 passes rearwardly into heating proximity or relation to the reservoir, so that when valve 83 is shut, the exhaust gases of the engine are availed of for heating the contents of the reservoir. Branch 84 is provided with a shut-off valve 85, so that when it is desired to turn off heat from the reservoir the exhaust gases may be discharged through branch 82, the valve 83 being open. Preferably, branch 84 is passed through the bottom of reservoir R and extended into a chambered container 86. This container is within the bottom portion of the supply reservoir. A series of pipes 87 pass from the container upwardly through the reservoir and discharge into the open air, above the top thereof. The cross-sectional areas of branches 82, 84, the capacity of the exhaust-gas arrester 86 and the cross-sectional areas of pipes 87 should be sufficient to allow the exhaust gases from the engine to escape without back pressure on the engine. The arrester is of considerable dimensions, so as to present a good amount of heated surface to the contents of the reservoir. It is obvious that such use of the hot gases in this

particular machine may be availed of through mechanical constructions quite different from the particular form of heating apparatus now shown, and that the heating apparatus shown within the reservoir may be heated by steam in a steam machine.

Discharge 77 of the supply reservoir extends downwardly to a horizontal, transverse distributing pipe 88, to which there is attached, by preference, a plurality of distributor-heads 89, in line one with another and of identical construction. Practically three distributor-heads are sufficient, and of course one continuous distributor-head might be used. In that case, however, the machine would frequently discharge superfluous material; for example, where only a narrow strip of the road-bed needed to be treated. This consideration applies more largely to repairing operations than it does to the initial surfacing of the road.

Each head is preferably hinged at 90 (Figs. 1; 12 and 13) to the distributing-pipe 88, the tubular neck 91 of the head having a transverse tubular portion 92 which is rockably mounted in a section 93 of pipe 88, this section 93 being a transverse tubular head on the lower end of discharge 77 and inclosing the part 92, which has an opening 94 for flow of material from discharge 77 into part 92 with which the tubular neck 91 communicates. Screw collars 95 couple sections of pipe 88 with the interposed transverse tubular head 93, which is circumferentially slotted at 96 to allow neck 91 to swing up and down in relation to distributing-pipe 88. Thus the distributor-heads will be lifted if they encounter an undue obstacle; or if it is desired to have them in raised position for any reason. A chain attachment 97 on frame A suffices to keep a head lifted (see Fig. 1). Each head is preferably provided with a bracket 98, against which the head abuts when in its lower or discharging position. A spring 99 attached to the bracket and to the head serves to hold the head in its proper discharging position against bracket 98. Each head is provided, in its tubular neck, with a shut-off valve 100. The distributor-heads are each preferably provided with downwardly and inwardly slanting side-walls 101, and are open on their under sides throughout their length for reception of an internal roof-shaped bottom 102, the bottom being secured to the end walls of the head, and the long sides of the bottom being removed from the opposed edges of the side-walls 101 so as to form two continuous parallel exits 103 along the under side of the distributor-head. The inclination of each side-wall of the roof-shaped bottom to a downwardly and inwardly slanting wall 101 forms, along each side of the distributor-head, a trough through which the surfacing material is directed to the

exits 103, being poured out thereof in continuous sheets, when both exits are open, one sheet being in advance of the other, and so being applied film-wise, one over the other, on the road-bed. To shut off one or both exits 103, and to regulate the width thereof, each side-wall 101 contains an upwardly extending slot 104, between its ends, these slots each forming a guide-way for a slide-plate 105 which projects from a slot to, into or across an exit for either opening or partially closing the same. The outer surface of each wall 101 is provided with a vertical slot 106, through which a stud 107 extends from a slide-plate. An adjusting-screw 108 is connected to the outer end of each stud and passed through an internally threaded ear 109 projecting from the head. By turning the screw, the slide-plate connected therewith may be moved into any desired position to close or open an exit. These discharge-heads may be made of any desired length, and, as above noted, one of them may be used in lieu of a plurality of them. When a plurality of heads are used, it is desirable that the opposite end portions of the exits 103 have endwise openings 103* (see Fig. 7), in order that the opposed end discharges of adjacent heads may intermingle, and so surface the road-bed along spaces corresponding to the distances between opposed ends of the distributor-heads. If provision of this sort were not made, then there would be danger, as will be apparent from Fig. 3, of the road-bed not being surfaced along such spaces.

The hot tarry or other surfacing material having been forcibly discharged on the road-bed, it remains to brush in this material; and for this purpose, rearwardly of the discharging-heads, two series of brushing-in brushes 110 are used. The members of each series of brushes are in line one with another, but at intervals apart; each member of the rear-most series being mounted opposite the interval between two members of the first series, so that a uniform brushing-in of the surfacing material from side to side thereof is secured. These brushes are each preferably hinged at 111, at its front edge, to a drag-rod 112 fast at its upper end on a transverse rocker-bar 113 mounted in side brackets 114 at the rear of frame A. Brushes 110 should be fairly heavy, and may be weighted whenever desired. Their purpose is to compress, brush-in and finish the surface of the hot or warm surfacing material.

The road-cleaning brush and the brushing-in brushes are in contact with the road surface, but use of the road-cleaning brush is not always required. To accommodate the machine to various positions when not in use for surfacing, and also to permit the brushing-in brushes to rise in case they hit a substantial obstacle, and to hold the drag-rods

and brushing in brushes in an elevated position, a cross-bar 115 is attached to the brackets 114 and hooks 116 mounted therein for reception of the drag-rods when the 5 brushes are to be kept raised.

The machine above described is particularly intended for the application of hot tar or tarry compositions, but it may be used for applying dissimilar compositions. The 10 tar or tarry compositions with which the supply reservoir is ordinarily to be charged will vary in consistency according to their ingredients and under varying temperamental conditions. Generally, however, the tar or 15 tarry compositions will be more or less thick and sticky. It would of course be possible to heat the tar or tarry compositions, and thus render them fluid enough to be readily pumped into the supply reservoir. In the 20 practical operation of my machine I propose, however, in order to obviate the expense, delay and inconvenience of heating tar before introducing it into the reservoir, to put it up in practically air-tight containers which 25 are to be distributed along the side of the road to be treated, at convenient intervals, whence it will be automatically conveyed to the reservoir as required. In order to accomplish the economical and convenient 30 charging of the reservoir under these conditions, I provide the container 200 (see Fig. 1) with two bung-holes in an upper side, and through one of them insert the nozzle 201 of a detachable pipe 202, the nozzle reaching to 35 near the bottom of the container. The other end of the pipe is attached to the tube 70 of the reservoir, and valve 71 opened. Into the other bung-hole of the container I insert a short nozzle 203 of a detachable pipe 204, and 40 attach the other end of this pipe to a compressed air-outlet 205 from the compressed air tank, this outlet being provided with a shut-off valve 206 which is opened when the charging is to take place. Valve 67 being 45 closed and valves 206 and 71 opened, compressed air will flow through pipe 204 against the upper portion of the contents of container 200, whereby the contents are forced 50 through pipe 202 and pipe 70 into the reservoir R to charge it, the man-hole cover being open to let air out of the reservoir. The principle here involved of charging the reservoir may obviously be carried out in steam-operated road-surfacing machines; for steam 55 from a steam generator passing through pipe 204 would push the contents of the container into the reservoir, just as the compressed air does. Therefore I desire to claim this feature of my invention broadly, whether the 60 expansive fluid generated and availed of is compressed air or steam, or any other expansive fluid under head or pressure.

I make no claim herein for the combination of the exhaust gas escape of an internal 65 combustion engine.

What I claim is:—

1. Apparatus for surfacing roads and the like, comprising, in operative combination, a wheeled vehicle; an internal combustion engine; a vehicle driving mechanism, and means for connecting it with and disconnecting it from the engine and vehicle; an air compressor, and means for connecting it with and disconnecting it from the engine; a reservoir provided at its upper end with an open-ended tube; a shut-off cock for the tube; and a discharging device at the lower portion of the reservoir; a conduit connection between the compression chamber of the air compressor and the upper portion of the reservoir; and an exhaust-gas conveyer mounted in heating proximity to the reservoir and connected with the exhaust-gas discharge of the engine. 70 75 80

2. Apparatus for surfacing roads and the like, comprising, in operative combination, a wheeled vehicle; an internal combustion engine; a vehicle driving mechanism, and means for connecting it with and disconnecting it from the engine and vehicle; an air compressor, and means for connecting it with and disconnecting it from the engine; a reservoir provided at its upper end with an open-ended tube; a shut-off cock for the tube; a discharging device at the lower portion of the reservoir; a compressed air tank; a pipe connecting said tank with the compression chamber of the compressor; a valve for said pipe; a pipe connecting the compressed air tank with the upper portion of the reservoir; and an exhaust-gas conveyer mounted in heating proximity to the reservoir and connected with the exhaust-gas discharge of the engine. 85 90 95 100

3. In a vehicle for surfacing roads and the like, the combination of a road-cleaning brush pivotally mounted on the frame of the apparatus; means for rotating the brush; a motor; means for connecting the motor with and disconnecting it from the brush-rotating means, and means for locking the brush in an adjusted position transversely diagonal to the length of the vehicle frame means for operatively connecting the motor with the driving mechanism of the vehicle; a reservoir; a discharge-head operatively connected with the reservoir; and means for heating the reservoir. 105 110 115

4. Apparatus for surfacing roads and the like, comprising, in operative combination, a wheeled vehicle; an internal combustion engine; a vehicle driving mechanism, and means for connecting it with and disconnecting it from the engine and vehicle; an air compressor, and means for connecting it with and disconnecting it from the engine; a reservoir; a discharging device at the lower portion of the reservoir; and a conduit connecting the air compressor with the upper por- 120 125 130

tion of the reservoir the latter being provided with a gas-escape near its upper portion.

5. Apparatus for surfacing roads and the like, comprising, in operative combination, a wheeled vehicle; an internal combustion engine; a vehicle driving mechanism, and means for connecting it with and disconnecting it from the engine and vehicle; an air compressor, and means for connecting it with and disconnecting it from the engine; a reservoir; a discharging device at the lower portion of the reservoir; a conduit connecting the air compressor with the upper portion of the reservoir; and means for automatically 10 heating the reservoir the latter being provided with a gas-escape near its upper portion.

6. In a vehicle for surfacing roads and the like, comprising a reservoir having at its 20 lower portion a discharge exit; a continuous transverse discharging-pipe communicating with said discharge exit; and a plurality of distributor-heads, each attached to said transverse discharging-pipe and communicating therewith in combination with means for 25 heating said reservoir; means for compressing air in the upper part of said reservoir, above the contents thereof; and means for propelling said vehicle.

30 7. The herein described discharging-head for a road-surfacing machine, comprising a receptacle which is provided with a bottom roof-shaped on its inner surface and with a

plurality of continuous exits along the length 35 of its bottom, in combination with a slide for opening or closing each exit, and means for adjusting the position of each slide a reservoir with which the discharging-head is operatively connected; means for heating 40 said reservoir; means for compressing a fluid in the upper part of said reservoir, above the contents thereof; and a motor for actuating the fluid-compressing mechanism and for generating heat to heat the reservoir. 45

8. In apparatus for surfacing roads and the like, the combination of a reservoir of the apparatus with an exterior container of the road-surfacing material; means carried by the apparatus for generating and propelling fluid of expansive force; means for conveying such fluid from its place of generation into the upper portion of the container, and means connecting the lower portion of the container with the reservoir, whereby the latter is automatically charged by expansion and force of the compressed fluid in the upper part of the container pushing its contents into and through the conduit the reservoir being provided with a gas-escape near 55 its upper portion. 60

In testimony whereof I have affixed my signature in presence of two witnesses.

COLIN MACRAE INGERSOLL.
